UNITED STATES PATENT OFFICE.

WALDEMAR KOPS, OF NEW YORK, N. Y.

GAS-MASK.

1,395,837.

Specification of Letters Patent.

Patented Nov. 1, 1921.

Application filed April 25, 1919. Serial No. 292,646.

To all whom it may concern:

Be it known that I, WALDEMAR KOPS, a citizen of the United States, residing in the borough of Manhattan, city, county, and 5 State of New York, have invented an Improvement in Gas-Masks, of which the following is a specification.

In the early production of gas masks, the same were made of flexible material which 10 was therefore collapsible in the use of the mask, and the masks were provided with nose clips to prevent the wearer from breathing through the nose and also with mouth pieces to be held in the mouth and gripped by the teeth, the mouth pieces being 15 connected to the hose or intake tube so that the wearer was compelled to breathe through the mouth. In the further development of gas masks, the hood or body of the 20 mask was molded out of suitable material over the necessary form in order to be adapted to fit the face of the wearer and to be sufficiently rigid to be non-collapsible. In masks of this type, the nose clips and mouth 25 pieces were dispensed with and the hose tube was connected to a deflector for directing the incoming air in such a way as to cause it to strike the interior of the lenses of the eye pieces so as to clarify the same and keep 30 them clear. There were obviously many disadvantages from a manufacturing standpoint in the molded gas masks and the object of my present invention is to overcome these disadvantages by producing a gas 35 mask from suitable materials worked up from blanks which are so formed and the parts connected as to make the mask substantially non-collapsible and at the same time of such a shape as to properly fit the 40 face of the wearer. In so doing, I preferably employ an outer blank of relatively stiff material and an inner blank of relatively flexible material. The outer blank is superimposed upon or otherwise connected 45 with the inner blank and connected thereto and the blanks stamped out with gores or V-shaped incisions in the required positions and the parts thus made suitably connected as hereinafter described to form the hood 50 or body of the mask.

In the drawing:

Figure 1 is a perspective view of the hood of a gas mask made in accordance with my present invention.

Fig. 2 is a side elevation of the mask before the same is completed. 55

Fig. 3 is a plan view of the blanks from which the hood of the mask is made, and

Fig. 4 is a section on line 4-4, Fig. 3.

Referring particularly to the drawing, it 60 will be seen that in carrying out this invention, I employ a blank or sheet of material indicated at 10, and this is preferably a relatively stiff impermeable rubberized fabric such as rubberized duck or sail cloth. I also 65 employ a blank or sheet of material indicated at 11 which is made of flexible material, such for example, as double stockinet. The blank 11 is appreciably larger than the blank 10 and the blank 10 is preferably superimposed upon the blank 11 in substantially the position shown in Fig. 3, and the parts cemented to one another and also 70 stitched along the edge of the blank 10 as indicated by the lines of stitching 12, or as 75 will be understood, these blanks may be otherwise suitably connected to each other so that the blank 10 in use is the outer blank and the blank 11 the inner blank. After the blanks 10 and 11 are thus secured 80 to one another, the eye piece openings 13 are suitably cut therein and preferably 85 slotted for appreciable distances as indicated at 14. In the blanks there is also cut an opening 15 for the hose tube of the mask and an opening 16 for connecting the flutter valve in position in the hood of the mask. Furthermore, in the mask blanks as hereinbefore described there are also cut darts or 90 or gores or V-shaped incisions 17 and 18 adjacent the eye piece sections of the hood, and darts or gores or V-shaped incisions 19 and 20 in the lower or chin section of the blank.

The edges of the darts or gores are then 95 zigzagged as indicated at 21 and 22 in Fig. 2, the former representing the zigzag edges in the eye piece darts or gores and the latter the zigzag edges of the gores in the chin section, and as illustrated in Fig. 2, 100 these zigzag edges of the gores are brought together and secured to one another in any suitable manner to form the hood of the mask. The edge of the blank 10 is then fitted with a tape 23 which is suitably secured thereto and extends along the entire periphery of the outer blank 10. The joint or seam made by connecting the edges of the eye darts 17 and 18 are then taped both 105

inside and outside as indicated at 24 and similarly the connected edges of the chin darts 19 and 20 are taped both inside and outside as indicated at 25 in order, as will 5 be understood to make the hood of the mask gas-tight.

The hood of the mask is also fitted with the eye pieces 26 secured in the openings 13, the hose tube 27 secured in the opening 10 15 and the flutter valve 28 secured in the opening 16. Also interiorly, the hood of the mask may be provided with a band or lining secured to or adjacent the edge thereof to form the joint between the hood and the 15 20 face of the wearer, and if necessary, this form of mask may also be provided with a chin piece.

It will be understood that the relatively stiff impermeable fabric used in the blank 20 10 when the mask is made as hereinbefore described, gives the hood sufficient rigidity to be substantially non-collapsible, and furthermore, that any suitable connections may be made for the hose tube and flutter valve 25 and that any desired type of harness may be employed for securing the hood or body of the mask in position on the head of the wearer.

I claim as my invention:

30 1. A gas mask made of blanks of flexible material, superimposed to reinforce the body of the hood of the mask and thereby prevent the entire front section of the hood from collapsing when in use and also to 35 provide a border section which is sufficiently yielding to permit a gas tight fit to be made between the same and the head of the wearer, the said blanks being provided with symmetrically placed incisions in the edges

thereof which are connected by a suitable 40 joint to completely form the hood of the mask.

2. A gas mask made from a blank of relatively flexible material and a blank of relatively stiff material, superimposed upon 45 the blank of relatively flexible material so as to reinforce the entire front section of the hood of the mask in order to prevent the same from collapsing and to cause the extending portion of the blank of flexible material to provide a border section which is sufficiently yielding to effect a gas tight fit between the same and the head of the wearer, the said blanks being provided with symmetrically placed incisions in the edges 50 55 thereof which are connected by a suitable joint to completely form the hood of the mask.

3. A gas mask made from a blank of relatively flexible material and a blank of relatively stiff material, superimposed upon the blank of relatively flexible material so as to reinforce the entire front section of the hood of the mask in order to prevent the same from collapsing and to cause the extending portion of the blank of flexible material to provide a border section which is sufficiently yielding to effect a gas tight fit between the same and the head of the wearer, the said blanks being provided with 60 65 symmetrically placed incisions in the sides thereof adjacent the eye sections, and also with symmetrically placed incisions in the lower edges thereof, the edges of said incisions being connected by suitable joints 70 75 to completely form the hood of the mask.

Signed by me this 21st day of April, 1919.
WALDEMAR KOPS.
